Walton Harrison
ATTORNEY

UNITED STATES PATENT OFFICE.

REUBEN ECKSTEIN, OF NEW YORK, N. Y.

CONNECTER.

Application filed April 14, 1921. Serial No. 461,266.

To all whom it may concern:

Be it known that I, REUBEN ECKSTEIN, a citizen of the United States, residing in the city of New York, county of Bronx, and State of New York, have invented certain new and useful Improvements in Connecters, of which the following is a true, clear, and concise description.

My invention relates to connectors, adapted for use in connecting lamps, fans, motors, heaters and other electrical devices of different kinds in order to facilitate energizing the same by means of electric currents.

More particularly stated, I seek to provide an electrical connector of unusually simple construction, made up of a relatively small number of parts and constructed of stock material, the various parts being each of such form as to enable it to be made in quantity, the parts being easily assembled, reliable in action, and easily standardized.

My invention further contemplates a connector so constructed and arranged that it may be quickly and accurately brought into or put out of use by a person of ordinary intelligence and having no special knowledge of electricity, and can while in active use rest upon a table or the like, or be suspended, which is safe in any position, and which presents a general appearance rather pleasing to the eye.

Reference is made to the accompanying drawing forming a part of this specification, and in which like reference characters indicate like parts throughout all of the figures.

Figure 1 is a view of my improved connector, showing the same as partly in elevation and partly broken away;

Figure 2 is a section on the line 2—2 of Figure 1, looking in the direction indicated by the arrows, and showing the plug as disconnected from the connector;

Figure 3 is a section on the line 3—3 of Figure 1, looking in the direction indicated by the arrows;

Figure 4 shows the contact plates alone, and is partly in elevation and partly broken away;

Figure 5 is a side view of the parts shown in Figure 4;

Figure 6 is a section on the line 6—6 of Figure 4, looking in the direction indicated by the arrows;

Figure 7 is a front elevation of the connector, showing it with three plugs in position, for supplying current to as many lamps or the like.

At 9 is a face plate of insulating material, and made rather thick and massive. It is provided with eight holes 10, 11, arranged in pairs as shown, each pair consisting of one hole 11 and one hole 10. Two stamping 12, 13, of sheet metal, preferably brass, copper or German silver, are secured together by brazing, soldering, welding, riveting, or in any other suitable manner. As thus united they comprise a single member which I designate as the front contact plate. The sheet stamping 12 is provided with four tongues 16, integral with it and located respectively at its four corners. The stamping 13 is similarly provided with four tongues 17, integral with it and located at its four corners. The stamping 13 being a little wider than the stamping 12, as indicated in Figures 4 and 5, each tongue 16 is spaced a very short distance from the mating tongue 17 immediately adjacent. Thus the tongues 16, 17, carried by the front contact plate are arranged in pairs, each pair consisting of a tongue 16 and a tongue 17.

The face plate 9 is provided with a recess 12^a, as shown more particularly in Figure 2, and the contact plate fits neatly into this recess, in such manner that each of the holes 11 is occupied by a pair of tongues 16, 17, the fit being rather loose in order to allow the tongues a little freedom of movement.

Two other sheet metal stampings 14, 15, are provided with tongues 18, 19 arranged in pairs as above described, the stampings 14, 15 being secured together in the same manner as the stampings 12, 13 and being as a whole designated as the back contact plate. The contact plate is mounted upon a plate 20 of insulating material, such as hard rubber, porcelain, or any of the well known compositions used as substitutes for hard rubber. I designate the plate 20 as middle

plate. The face plate 9 and the middle plate 20 are preferably made of the same material, but this is not essential. The middle plate is provided with a recess 20^a, into which the back contact plate is sunken, as indicated more particularly in Figure 2, the parts being so arranged that when the back contact plate is in position the tongues 18, 19 extend through the holes 10, in the same manner that the tongues 16, 17, extend through the holes 11 as above described.

A third plate of insulating material is shown at 21, and for convenience is designated as the retaining plate.

18 A number of screw bolts 22, in this instance four, each extend through holes in the three plates of insulating material, so as to hold various parts together. The bolts 22 are severally provided with heads 23 and with revoluble nuts 24. These heads and nuts are sunken by means of holes 25, 26.

A lamp cord 27, of the kind known as a double cord, comprises a pair of single cords 28, 29, each being secured by a solder 25 joint 30 to one or the other of the contact plates. The front plate 9 is provided with a channel 9^a, merging into the recess 12^a, and the middle plate 20 is similarly provided with a channel 20^a, merging into the 30 recess 20^a, the channels 9^a and 20^a being used as passages for holding the cords 29, 28.

Associated with the connector are plugs 31, of which three are here shown. The connector as here shown and described is 35 adapted for use with four such plugs, but obviously the number may be varied. Each plug 31 is provided with a lamp cord 32 wherewith it is supplied with electric current, and from which it may be suspended.

40 Each plug 31 is provided with a pair of contact blades 33, 34, so arranged that by using the plug as a handle the blades may be thrust into a pair of the holes 10, 11, so that one of the blades engages a pair of tongues 45 16, 17, the other of the two blades engaging the mating pair of tongues 18, 19.

Each lamp cord 32 leads from its plug 31 to a lamp, a fan, a heater or the like, to be energized.

50 The connector as a whole is adapted to be suspended or rested upon a table or the like, and is so finished and proportioned as to present to the eye an attractive appearance.

55 The operation of my device may be readily understood in the light of the foregoing description. The various parts being assembled and arranged as illustrated and described, the connector is either suspended

60 by means of the double cord connected with it or is rested upon a table or the like, and is then ready for use. Then, whenever the operator desires to supply current to a lamp or the like, he merely inserts one or more

of the plugs, as required. The plugs are 65 simply pulled out in order to disconnect the lamps or analogous devices from the source of the electric current.

My improved connector can be safely handled by persons not specially familiar with 70 electrical appliances. It is fool proof, in that no metallic parts capable of being charged are exposed.

This connector is of a form well adapted 75 for conserving both time and material in its manufacture. It is well adapted for quantity production. Its various parts can easily be made from general stock material, and the different individual parts may readily be standardized.

80 I do not limit myself to the particular mechanism shown, as variations may be made therein without departing from the spirit of my invention, the scope of which is commensurate with my claims.

I claim—

1. The combination of a plate of insulating material provided with a number of holes extending through it, a contact plate 90 mounted upon said plate of insulating material and provided with tongues of conducting material extending through some of said holes and arranged in pairs, a second plate of insulating material connected with said first-mentioned plate of insulating material and provided with holes extending therethrough and a second contact plate, said second contact plate being provided with tongues of conducting material arranged in pairs and extending through the holes in said second plate of insulating material and also through some of the holes in said first-mentioned plate of insulating material.

100 2. In a connector the combination of a plate of insulating material provided with a number of holes extending through it, a contact plate carried by said plate of insulating material and provided with tongues arranged in pairs and extending through some of said holes, a second plate of insulating material provided with holes registering with some of said first-mentioned holes,

110 a contact plate carried by said second plate of insulating material and provided with tongues arranged in pairs and extending through said holes in said second plate and through the holes of the first-mentioned plate in registry therewith, a third plate of insulating material engaging said second-mentioned contact plate, and bolts extending through all of the plates of insulating material, for holding the same together.

115 3. In a connector, the combination of a plate of insulating material provided with holes extending through it and further provided with a recess into which said holes merge, a contact plate of conducting ma-

terial located within said recess and provided with tongues arranged in pairs and extending through some of said holes, a second plate of insulating material mounted upon said first-mentioned plate of insulating material and provided with holes registering with some of said holes thereof, and

a contact plate mounted upon said second-mentioned plate of insulating material and provided with tongues arranged in pairs and extending through the holes in said second-mentioned plate and through some of the holes in said first-mentioned plate. 10

REUBEN ECKSTEIN.
